(57) **CLAIM**

The ornamental design for a shear gate, as shown and described.

DESCRIPTION

FIG. 1 is a front view of a shear gate showing my new design;

FIG. 2 is a back view thereof;

FIG. 3 is a bottom view thereof;

FIG. 4 is a top view thereof;

FIG. 5 is a right side view thereof;

FIG. 6 is a left side view thereof;

FIG. 7 is a front view in an open configuration thereof; and, FIG. 8 is a perspective view thereof.

The even-length broken lines are directed to environment, represent unclaimed subject matter, and form no part of the claimed design.
